PHONOGRAPHIC APPARATUS

Henry E. Roys, Indianapolis, Ind., assignor to
 Radio Corporation of America, a corporation
 of Delaware

Application May 29, 1944, Serial No. 537,915

3 Claims. (Cl. 274—25)

1

This invention relates to phonographic apparatus, and more particularly to a recording device for recording signals on a record blank.

In certain types of sound recording apparatus, it has been found advantageous to employ a so-called "advance ball" (a) for supporting the weight of the recording head and thus largely relieving the recording stylus of this burden, and (b) for controlling the depth of penetration of the recording stylus into the record, whereby to control the depth of the groove formed by the stylus in the blank. With certain types of sound recording machines, particularly those operating on discs record blanks, it is possible to arrange the recorder head to be driven in either one of two opposite directions across the record. Thus, in the case of disc recording machines of this type, the recording head may be arranged to move radially over the disc either from a point near the periphery thereof toward its center for "outside-in" recording, or from adjacent the center of the disc toward the periphery thereof for "inside-out" recording.

In prior art recording machines employing an advance ball, the ball is mounted in a fixed location on the recorder head somewhat in advance of the recording stylus in the direction of movement of the recorder head across the record. Obviously, therefore, any given recorder head provided with such an advance ball will be suitable either for outside-in recording or for inside-out recording, but not for both because a fixed advance ball can be in advance of the recording stylus on only one side thereof. Considered from this aspect, then, it is apparent that a recording machine otherwise useful for either outside-in or inside-out recording becomes limited to recording in only one direction if an advance ball is to be used on the recording head thereof according to customary practice.

The primary object of my present invention, therefore, is to provide an improved two-way recording apparatus which will be free from the above mentioned limitation.

More particularly, it is an object of my present invention to provide, in a sound recording machine, an improved recording head which is provided with an advance ball and which can, nevertheless, be used for either inside-out or outside-in recording.

Another object of my present invention is to provide a novel advance ball attachment for phonographic recorders employing recording styluses, which attachment is arranged to dispose the advance ball on either side of the recording

2

stylus to thereby render such recorders suitable for either outside-in or inside-out recording on disc records.

Still another object of my invention is to provide an advance ball attachment as aforesaid which can be applied quite readily to existing recorder heads.

A further object of my present invention is to provide an improved advance ball recorder head as above set forth wherein the depth of cut of the recording stylus in the record blank can be controlled regardless of whether the recorder is set for inside-out recording or for outside-in recording.

15 Additional objects of my present invention are to provide an improved advance ball recorder head as above described which is of sturdy construction, which can be readily adjusted and set for operation even by one not highly skilled in the art, which is inexpensive in cost and readily lends itself to quantity production, and which is extremely efficient in use.

The foregoing and other objects of my invention I accomplish by providing on a recorder head 25 employing a recording stylus an adjustable holder for the advance ball consisting of a flat plate, preferably of resilient or spring material. The plate may be attached to the under side of the recorder head with a pair of screws which extend 30 through slots in the plate. These slots are arranged to permit transverse movement of the plate relative to the recording stylus so that an advance ball carried thereby may be located on either side of the stylus. In this way, the recorder head may be set for either outside-in or 35 inside-out recording, as desired. The resilient plate may be given an initial set to bias it against a vertical adjusting screw by means of which the advance ball may be given vertical adjustment,

40 or adjustment in a direction parallel to the axis of the recording stylus for the purpose of regulating the depth of cut of the stylus. The plate may be arranged in such relation to the vertical adjusting screw that it acts as a cantilever beam 45 clamped at one end by the screws extending through the aforementioned slots therein and freely suspended at its opposite end with which the vertical adjusting screw is in engagement.

The novel features that I consider characteristic of my invention are set forth with particularity in the appended claims. The invention itself, however, both as to its organization and method of operation, as well as additional objects and advantages thereof, will best be understood from the following description of one em-

bodiment thereof, when read in connection with the accompanying drawing, in which

Figure 1 is a sectional view of a recorder head taken along the line I—I of Fig. 2, and showing my improved advance ball attachment applied thereto.

Figure 2 is a sectional view taken on the line II—II of Fig. 1.

Figure 3 is a front elevation of the recorder head.

Figure 4 is a bottom plan view thereof showing the advance ball positioned for outside-in recording, and

Figure 5 is a view similar to Fig. 4 but showing the advance ball positioned for inside-out recording.

Referring more particularly to the drawing, wherein similar reference characters designate corresponding parts throughout, there is shown a recorder head 1 having a cover 3 in which are enclosed the operative parts for driving a recording stylus 5 at the frequency of the signals to be recorded. The recorder may be of any suitable or approved form and, merely by way of illustration, is shown as being of the magnetic type. The particular recorder head illustrated includes a magnet 7 which supplies flux to a pair of pole pieces 9 having an air gap 11 therebetween and provided with a space for the reception of a coil 13. A socket or other suitable clamping member 15 is provided with an armature 17 which terminates in the air gap 11. A centering spring 19 attached to the socket 15 serves to restore the armature 17 to centered position in the air gap 11 and may be adjusted to properly center the armature 17 in the air gap 11 by a plurality of adjusting screws 21. The recording stylus 5 is held in the socket 15 by a set screw 23.

The construction thus far described is more or less conventional and therefore no further description thereof is believed to be necessary. Suffice it to say merely that signal voltages applied to the coil 13 will produce a flux which will either aid or oppose the flux in the air gap 11 and hence cause the armature 17 to vibrate in correspondence with the applied signals. This, in turn, effects similar vibration of the stylus 5 and causes it to cut a groove in a record blank (not shown) which it engages.

Mounted on the bottom of the recorder head 1 is a plate 25 provided with a pair of longitudinal slots 27 through which extend a pair of screws 29 for adjustably securing the plate 25 to the bottom of the recorder head 1. The plate 25 is preferably of resilient material and may be provided with a transverse slot 31 which aids in forming a hinge along approximately the dash lines 33 for a purpose to be presently set forth. Preferably, although not necessarily, the plate 25 may be provided with a downwardly extending flange 35 for stiffening the portion of the plate 25 between the hinge portion 33 and the freely suspended, right-hand end thereof, as viewed in Figs. 2, 4 and 5.

Between its hinge portion 33, 33 and its freely suspended end, the plate 25 is provided with a socket or clamping member 37 in which an advance ball 39 is firmly clamped by means of a screw 41 or the like. The clamping member 37 may be secured to the plate 25 in any suitable manner, as by rivets, spot welding, or the like 43. A vertically extending adjusting screw 45 passes through the recorder head and engages the upper portion of the plate 25 adjacent the freely suspended end thereof, as best seen in Fig. 2. To 70

insure constant engagement of the plate 25 with the screw 45, the plate 25 may be given an initial set or bias so that, when it is clamped in place by the screws 29, the freely suspended end thereof 5 will bear against the lower end of the screw 45.

It will be apparent from the foregoing description that, merely by loosening the screws 29 and shifting the plate 25 transversely of the recorder head 1 in directions transverse to the axis 10 of the stylus 5, as indicated by the arrow A in Fig. 4 and the arrow B in Fig. 5, the advance ball 39 may be located or disposed either on the right or on the left of the stylus 5, as viewed in Fig. 2. When the plate 4 is moved in the direction of the 15 arrow A and is clamped by the screws 29 in the position shown in Fig. 4, the recorder is set for outside-in recording on a disc record blank. On the other hand, by merely loosening the screws 29, shifting the plate 25 in the direction of the 20 arrow B to the position shown in Fig. 5, and then tightening the screws 29 again, the advance ball 39 will be located on the opposite side of the stylus 5, thereby rendering the recorder suitable 25 for inside-out recording. As illustrated in the drawing, the advance ball is so located with respect to the stylus 5 that the latter must first be removed before the plate 25 can be shifted from one position to the other. However, it is apparent 30 that the advance ball 39 may be so located with respect to the stylus that it will clear the stylus when the plate 25 is shifted from one position to the other, in which case it will not be necessary to first remove the stylus 5.

As will be seen from Figs. 1, 2 and 3, the stylus 35 5 has its tip extending somewhat below the lower extremity of the advance ball. During operation 40 of the recorder head, the advance ball rides on the surface of the record blank in advance of the stylus 5 in the direction of movement of the head over the record while the stylus 5 penetrates into the record, and the difference in height between the tips of the stylus 5 and the advance ball 39 determines the depth of cut of the recording stylus. By merely manipulating the adjusting 45 screw 45 in one direction or the other, the plate 25 can be caused to bend slightly along the hinge 33, 33 to thereby adjust the advance ball 39 vertically, or in a direction substantially parallel to the axis of the stylus 5. In this way, the 50 depth of cut of the stylus can be readily set regardless of whether the recorder is conditioned for inside-out recording or for outside-in recording. However, once the depth of cut of the stylus 5 has been set by the screw 45, shifting the plate 55 25 to either one or the other of the two positions shown in Figs. 4 and 5 will not appreciably alter this depth.

From the foregoing description, it will be apparent to those skilled in the art that I have 60 provided an advance ball attachment which can be applied to existing recorder heads, if desired, and which can be adjusted easily for either inside-out or outside-in recording by locating the 65 advance ball on either side of the recording stylus. Although I have shown and described but one embodiment of my invention, it will undoubtedly be apparent that many other modifications, as well as changes in the one described, are possible within the scope of my present invention. I therefore desire that this invention shall not be limited except insofar as is made necessary by the prior art and by the spirit of the appended claims.

I claim as my invention:

1. In a signal recording device, the combina-

tion of a recording head, a stylus vibratively supported thereby for cooperation with a record, means associated with said stylus for imparting thereto vibrations to be recorded, an advance ball mounted on said recording head associated with said stylus for contact with the surface of the record whereby to determine the depth to which said stylus will penetrate the record, means adjustably mounting said advance ball for movement thereof in a plane normal to said stylus to one or another of two positions on opposite sides of said stylus and laterally with respect to the tracking movement of said stylus without altering a present stylus penetration depth, and adjustable means associated with said last named means for moving said advance ball in a plane substantially parallel to said stylus whereby to alter said penetration depth, said mounting means comprising an adjustable plate having a resilient hinge portion at one side thereof, said hinge portion including a slot along the hinge axis thereof, and a freely suspended end portion beyond said hinge portion.

2. In a signal recording device, the combination of a recording head, a stylus vibratively supported thereby for cooperation with a record, means associated with said stylus for imparting thereto vibrations to be recorded, an advance ball mounted on said recording head associated with said stylus for contact with the surface of the record whereby to determine the depth to which said stylus will penetrate the record, means adjustably mounting said advance ball for movement thereof in a plane normal to said stylus to one or another of two positions on opposite sides of said stylus and laterally with respect to the tracking movement of said stylus without altering a preset stylus penetration depth, and adjustable means associated with said last named means for moving said advance ball in a plane substantially parallel to said stylus whereby to alter said penetration depth, said mounting means comprising an adjustable plate having a resilient hinge portion at one side thereof, said hinge portion including a slot along the hinge axis thereof, and a freely suspended end portion beyond said hinge portion, further characterized in that said adjustable means contacts said mounting means adjacent its freely suspended end whereby said stylus and said advance ball

5 vance ball will be located in planes lying between said hinge portion and said adjustable means.

3. In a signal recording device, the combination of a recording head, a stylus vibratively supported thereby for cooperation with a record, means associated with said stylus for imparting thereto vibrations to be recorded, an advance ball mounted on said recording head associated with said stylus for contact with the surface of the record whereby to determine the depth to which said stylus will penetrate the record, means adjustably mounting said advance ball for movement thereof in a plane normal to said stylus to one or other of two positions on opposite sides of said stylus and laterally with respect to the tracking movement of said stylus without altering a preset stylus penetration depth, and adjustable means associated with said last named means for moving said advance ball in a plane substantially parallel to said stylus whereby to alter said penetration depth, said mounting means comprising an adjustable plate having a resilient hinge portion at one side thereof, said hinge portion including a slot along the hinge axis thereof, and a freely suspended end portion beyond said hinge portion, further characterized in that said adjustable means contacts said mounting means adjacent its freely suspended end whereby said stylus and said advance ball
